His Attorney.

UNITED STATES PATENT OFFICE.

ARTHUR D. ROBINSON, OF LOGAN, WEST VIRGINIA.

DESICCATING APPARATUS.

1,330,747.

Specification of Letters Patent. Patented Feb. 10, 1920.

Application filed November 11, 1918. Serial No. 262,096.

To all whom it may concern:

Be it known that I, ARTHUR D. ROBINSON, a citizen of the United States, residing at Logan, in the county of Logan and the State 5 of West Virginia, have invented a new and useful Improvement in Desiccating Apparatus, of which the following is a full, clear, and exact specification, reference being had to the accompanying drawings, which form 10 a part thereof.

My invention relates to desiccating apparatus used for the purpose of drying eggs or similar substances in which the substance to be dried is applied to a moving belt while 15 in a batter-like condition, and then carried by the belt into and through a hot air chamber where the batter is subjected to the action of hot air and thereby dried. My invention relates particularly to the means 20 whereby the hot air is distributed and made to come in contact with the substance to be dried in such a way that the drying is substantially uniform throughout the whole width of the carrying belt.

25 The object of my invention is to provide means whereby the air is made to flow from a hot air chamber onto the carrying belt in such a way that the substance to be dried will be quickly and uniformly dried throughout the width of the belt; and a 30 further object of my invention is to provide means whereby the moving belt is retained in position as it passes through the drying chamber, thus avoiding friction and the loss 35 of material due to imperfect drying or to the belt running out of place while in the drying chamber.

My invention is fully shown in the accompanying drawings where similar numerals are used to designate similar parts.

40 Figure 1 is a longitudinal sectional view of an apparatus embodying my invention; Fig. 2 is a vertical sectional view through the apparatus on the line 2—2 of Fig. 1; 45 Figs. 3 and 4 are enlarged views showing reversed and in detail certain features of construction of the apparatus; and Figs. 5 and 6 are enlarged views of the device used for guiding the belt.

50 Referring to the figures, 1 is the frame of the apparatus in which is mounted an endless belt 2. This belt is mounted on drums 3 and 4 and it is driven by means of a driving belt, not shown, which passes over the 55 driving pulley 5 mounted on the shaft of the

drum 4. In the apparatus the belt is shown as moving in the direction indicated by the arrows, that is to say, the upper part of the belt moves from the right toward the left and the lower part moves from the left toward the right. The belt is supported at intervals by means of rollers 6, and in order to cause the belt to run true through the apparatus guides 7 are provided. I have shown only two sets of these guides, one for 60 the upper run of the belt and one for the lower run, but it is evident that as many may be provided as the length of the belt makes necessary or desirable. 8 is a supply pipe through which the eggs to be desiccated 65 are brought in a batter condition to the apparatus, and from which pipe the egg batter is fed onto the upper surface of the belt 2 by means of a suitable nozzle 9. It is to be understood that special devices are provided whereby the eggs to be dried are reduced to a batter-like condition and caused to move from a source of supply through the pipe 8 up to the apparatus, but since 70 these devices form no part of my invention they are not shown here. It is also to be understood that the nozzle 9 may be of my convenient or proper shape to as nearly as possible evenly apply the batter to the 75 surface of the belt 2. After the batter has been dried it remains adhering to the belt and is scraped therefrom by means of suitable scrapers 10, which are arranged to be brought into contact with the belt when desired. 11 is a hot air chamber to which 80 heated air is supplied, preferably, under a slight pressure, and which has a bottom wall 12 which lies close to and immediately 85 above the upper surface of the upper run of the belt 2. In order that the batter applied to the belt 2 may be uniformly and quickly dried it is necessary that the hot air be made to pass from the chamber 11 through the wall 12 so as to impinge upon the upper surface of the belt 2 in as nearly 90 as possible a uniform manner throughout the whole width of the belt and without sufficient force to cause the dried material to be dislodged and blown from the belt. To accomplish this I form in the wall 12 a plurality of rows of perforations 13 extending crosswise of the length of the belt, and these 95 perforations I preferably make rectangular in shape. I have found by actual trial that it is preferable to make the perforations of 100

105 110

one row alternate with those of adjacent rows, and I have also found that better and more uniform results in drying are obtained if I place in front of each aperture a deflecting plate 14. By in front of the aperture I mean on that side of the aperture which lies closest to that end of the chamber 11 toward which the hot air is flowing. I have found that it is not necessary to make these deflectors very high or to make them higher for some rows than others. A cheap and effective manner of applying these deflectors is that shown in Figs. 3 and 4, where the deflectors 14 are shown made of a strip of metal bent longitudinally so as to have a base portion 17 at right angles to that part which acts as a deflector, and by means of this base portion 17 the strip may be fastened to the upper surface of the wall 12 so that a single strip will act as a deflector for a whole row of apertures. This construction is cheap and very effective and is preferable to a construction in which there is a single separate baffle plate for each aperture. The air which passes through the aperture 13 in the wall 12 spreads out over the batter to be dried on the belt 2, and because of its heat the batter is dried and the moisture is carried away by the moving air. The air moves toward the side edges of the belt and passes down over these into the chamber 15 and from this it passes out through the vent shaft 16. I preferably make the apertures 13 elongated, and make those of one row alternate with those of adjacent rows as shown in Fig. 4, and I also preferably make the length of an aperture substantially the same as or slightly greater than the space between adjacent apertures in the adjacent row. This insures that every part of the surface of the upper run of the belt 2 is uniformly and equally acted upon by the hot air from the chamber 11.

In order to further insure the uniformity of drying of the batter put on the belt 2 it is desirable that the belt shall weave side-wise, as it passes from the drum 3 to the drum 4, as little as possible. And to prevent this weaving I provide guides 7. These guides are shown in detail in Figs. 5 and 6, and are applied to the belt in pairs, one on each side of the belt. Each one of the pair of guides comprises a stationary strip 20 to which is bolted by means of the bolts 21 top and bottom members 22 and 23, respectively. 24 is a contact member which is mounted so that it can move to and from the strip 20 between the members 22 and 23. The member 24 is, preferably, elongated and provided with a groove 25 adapted to receive the edge of the belt 2. The member 24 is held in place by means of bolts 26 which pass through the slotted openings 27 formed in 24. Between the movable member 24 and the fixed member

20 there are springs 28 which tend to hold the member 24 in place against any edge pressure of the belt. These springs have their ends in suitable recesses 29 and 30 formed in the members 20 and 24, respectively. If for any cause the belt tends to weave or move side-wise the edge of the belt will press against the bottom of the slot 25 and thus tend to move the member 24 side-wise against the fixed member 20. Movement of the member 24 will, however, be resisted by the action of the springs 28 and thus pressure will be exerted on the edge of the belt 2 by which the belt will be prevented from weaving.

The groove or slot 25 into which the edge of the belt runs, not only prevents the belt from flapping up and down, but it also increases the resistance to the turning up of the edge of the belt. When there is no slot the edge of the belt can be turned up by bending the material of the belt only once, but when there is a slot the material of the belt must be bent twice in order to turn up the belt, and even then the edge of the belt remains flat or horizontal. The slot makes it just twice as difficult to cause the belt to be bent upward by pressure of the edge of the belt against the guide; and the slot confines the pressure to the edge of the belt and prevents the under side of the belt near the edge from contacting with the guide.

The presence of the springs 28 makes the guides resilient so that a yielding force is exerted against the edge of the belt instead of an unyielding force such as is exerted by a rigid guide, and the force exerted by the guides against the edge of the belt is a gradually increasing one that becomes greater the more the belt actually deviates from its proper path. This yielding of the guide to accommodate itself to the weaving of the belt while exerting a gradually increasing resistance to the weaving conserves the belt by reducing the wear on the edges and avoiding crimping or turning up the margins thereof.

What I claim as new and desire to secure by Letters Patent, is:

1. In an apparatus for desiccating eggs and the like, a belt having a horizontally disposed carrying part, a hot air chamber having a horizontal wall in proximity to and above the carrying part of said belt and said wall having perforations therethrough arranged in rows transversely of said belt, and deflectors in said chamber for equalizing the flow of air through said perforations, each of said deflectors consisting of a strip standing upright in front of a row of perforations.

2. In an apparatus for desiccating eggs and the like, a belt having a horizontally disposed carrying part, a hot air chamber

having a horizontal wall in proximity to and above the carrying part of said belt and said wall having perforations therethrough arranged in rows transversely of said belt 5 with the perforations of one row alternating with those of adjacent rows, and deflectors in said chamber for equalizing the flow of air through said perforations, each of said deflectors consisting of a strip standing upright in front of a row of perforations.

3. In an apparatus for desiccating eggs and the like, a belt having a horizontally disposed carrying part, a hot air chamber 15 having a horizontal wall in proximity to and above the carrying part of said belt and said wall having perforations therethrough which are elongated in shape and arranged in rows transversely of said belt 20 with the perforations being as long as the distance between the perforations and those of one row alternating with those of adjacent rows, and deflectors in said chamber for equalizing the flow of air through said 25 perforations, each of said deflectors consisting of a strip standing upright in front of a row of perforations.

4. In an apparatus for desiccating eggs and the like, a belt having a horizontally 30 disposed carrying part, a hot air chamber having a horizontal wall in proximity to and above the carrying part of said belt and said wall having perforations therethrough,

and resilient guides having slots adapted to receive the edges of said belt whereby weaving thereof is prevented. 35

5. In an apparatus for desiccating eggs and the like, a belt having a horizontally disposed carrying part, a hot air chamber having a horizontal wall in proximity to and above the carrying part of said belt and said wall having perforations therethrough, deflectors in said chamber for equalizing the flow of air through said 40 perforations, and resilient guides having slots 45 adapted to receive the edges of said belt whereby weaving thereof is prevented.

6. In an apparatus for desiccating eggs and the like, a belt having a horizontally disposed carrying part, a hot air chamber 50 having a horizontal wall in proximity to and above the carrying part of said belt and said wall having perforations therethrough arranged in rows transversely of said belt with the perforations of one row alternating 55 with those of adjacent rows, deflectors in said chamber for equalizing the flow of air through said perforations, each of said deflectors consisting of a strip standing upright in front of a row of perforations, and resilient guides having slots adapted to receive the edges of said belt whereby weaving 60 thereof is prevented.

In witness whereof I have signed my name to this specification.

ARTHUR D. ROBINSON.
